UNITED STATES PATENT OFFICE.

HARVEY HARDING, OF EAST ORANGE, NEW JERSEY.

BOILER.

Application filed March 13, 1922. Serial No. 543,284.

To all whom it may concern:

Be it known that I, HARVEY HARDING, a citizen of the United States, residing at East Orange, in the county of Essex and 5 State of New Jersey, have invented new and useful Improvements in Boilers, of which the following is a specification.

This invention relates to improvements in boilers, and the principal object is to devise 10 means whereby the tubes may be rendered electro-negative for a considerable portion or all of their length without interfering with the expansion and contraction of the tube connections which has been found in 15 practice to be essential.

Another object is to so arrange contacting metals as to render the tubes electro-negative and thereby prevent pitting of the same.

With these and other objects in view, the 20 invention resides in certain construction, the essential features of which are hereinafter fully described, are particularly pointed out in the appended claims, and are illustrated in the accompanying drawing, in which:—

25 Figure 1 is a fragmentary view of a portion of a boiler, showing the manner of supporting a tube.

Figure 2 is an exaggerated detail view of the means of securing a tube in place.

30 Like characters of reference refer to like parts in both views.

In the tubes of locomotive boilers, ship boilers, and the like it has been demonstrated that owing to the heating of the end of the 35 tube 10 near the firebox 11, and the fact that this end of the tube is mounted in a collar 12 of copper or brass to permit of rapid expansion and contraction, thermo-electric currents are set up near the firebox.

40 As the tubes are surrounded by water which in most instances becomes more or less impure so as to act as an electrolyte, the current flowing from the tube to the collar sets up an electrolysis whereby the tube is pitted. The tube therefore is quickly rendered 45 unserviceable, and it is then necessary to insert an entire new tube or to cut off the pitted portion and weld on a new piece in its place.

This pitting of the tube has been known 50 for some time to be due to electric activity, but it has been supposed that this was of galvanic nature as between various particles in the tube. However, it will be readily seen that the thermo-electric action is responsible for this, when it is remembered 55 that the steel tube is seated in a copper col-

lar, and corresponds to the similar construction used in pyrometers. To overcome this condition, the only thing that has been so far attempted with any degree of success has 60 been the treatment of the water so as to remove its electrolytic action. But the difficulty with this method is that it must be one-hundred per cent perfect in analysis and action if it is not to do more harm than 65 good. If a few per cent too much of the treatment mixture is added to the water, then the boiler will foam, greatly reducing the efficiency of the steam; and if too little is used a coating of lime will be formed on 70 the tubes. Also the expense in keeping up the necessary chemical laboratories and equipment is well-nigh prohibitive.

In carrying the present invention into effect, the boiler tubes are copper plated either 75 their entire length or to such an extent as will entirely copper the portion of the tubes which is subject to thermo-electric action from the heat of the fire box. In the drawing the copper plate is greatly exaggerated 80 in the showing in Figure 2 and is indicated by the numeral 14. The copper plate of the tube being in contact with the copper collar 12, no thermo-electric currents are set up, and the pitting of the tube is thereby eliminated, and the tube will not become coated with lime or other shell, while, at the same time, the essential expansion and contraction of the tube connection is not interfered with.

It will be seen that by my novel means I 90 have produced tubes and tube connections for boilers, which will resist decomposition and effectually eliminate galvanic or thermo-electric action or oxidation without interfering with the essential expansion and contraction 95 of the connections.

What is claimed as new is:—

1. The combination in a boiler construction, of an apertured tube sheet, flue tubes extending transversely through the apertures of the sheet and secured at one end to the sheet, copper collars lining the apertures of the tube sheet, and coatings of copper on and exterior of the tubes and extending a distance from the tube sheet and interposed 100 between the said tubes and the copper collars, whereby without interfering with the essential expansion and contraction of the tube connections passage of electric current 105 from the tubes through the water to the 110 collars is prevented.
2. The combination in a boiler construc-

tion of an apertured tube sheet, flue tubes extending transversely through the apertures of the sheet and secured at one end to the sheet, and copper collars lining the apertures of the tube sheet and surrounding the flue tubes; the said flue tubes being exteriorly copper plated throughout the interior of the copper collars and for a distance inwardly

from the tube sheet whereby without interfering with the essential expansion and contraction of the tube connections passage of electric current from the tubes through the water to the collars is prevented.

In testimony whereof I have affixed my signature.

HARVEY HARDING
